tion of Delaware

Application January 14, 1933, Serial No. 651,810

5 Claims. (Cl. 179—171)

This invention relates to an oscillating system and especially to an oscillating system of the cathode-ray type used for the production of ultra-short wave length electrical energy.

It is an object of the present invention to provide a cathode-ray oscillating system especially adapted for the efficient generation of ultra short wave length electrical energy. To provide such a system, according to the present invention, proper consideration is made for the time lag and impedance changes along the control electrodes or deflecting electrodes, and targets, power electrodes or plates of the cathode-ray oscillator. That is, by properly associating with the electrodes of the oscillator, suitable tuned circuits and, by suitably coupling the circuits together by means of adjustable transmission lines, correct conditions for ultra short wave length electrical energy may be had, which conditions were heretofore unattainable with ordinary tuned circuits and inductive supply of energy to the deflecting electrodes.

The invention is more fully described in connection with the accompanying drawing which, it is to be clearly understood, is only illustrative of the present invention. The drawing schematically illustrates a cathode-ray oscillator for efficiently generating electrical energy at ultra short wave lengths.

Referring to the drawing, means are provided for the production of a concentrated stream of electrons comprising a cathode 2, mounted within an evacuated container 3 energized by the action of a suitable transformer 4 supplied with alternating heating energy. Electrons emanating from the cathode are concentrated by the action of an annular electrode 6 maintained at a suitable negative potential by virtue of the conductor 8 coupling it to source of potential 10.

Flow of the concentrated stream of electrons is caused by the attraction of cylindrical anode 12, polarized to a high positive potential by connection through a protective resistor 15 to source 10. Anode cylinder 12, offering no obstruction to the path of the electron stream, allows it impinge, when properly deflected by the action of deflector plates or control electrodes 14, 16, against the anodes or target electrodes 18, 20 placed in the path of the deflected electron stream.

The targets 18, 20, are coupled to a tuned circuit 22 formed of an adjustable U-shaped metallic conductor 24. A similar circuit 26 is connected to the deflecting electrodes 14, 16 and connected to the anode circuit 22 by means of transmission line 34.

The deflecting electrodes are connected through circuit 26 at the voltage nodal point thereof through protective resistor 27 to a suitable source of polarizing potential 28. The protective resistors are inserted as they tend to prevent short circuiting of the sources of potential should any of the electrodes become grounded, and, since they offer some protection to operators in the event that they should happen to touch the bare metallic tuned circuits 22, 26. Polarizing potential is supplied in a similar fashion to the target electrodes 18, 20 from another source of potential 30 through another protective resistor 32.

As already indicated, the tuned circuits 22, 26 are coupled together by means of a transmission line 34, coupled to suitable impedance points in circuits 22, 26 having in series therewith U-shaped metallic slides 36, 38 for varying the effective length thereof. Condensers 40, 42 are also placed in series with the line in order to prevent cross application of potentials from sources 30, 28.

The electron stream, indicated by dotted lines, passing between the control electrodes 14, 16 towards the electrical center between the two target electrodes, will if a disturbance occurs on the electrodes, be deflected so as to hit one of the two targets 18, 20. By virtue of this shock excitation of circuit 22, a current impulse is created flowing through the U-shaped slide 24 connecting the two target electrodes. The time constant of this impulse will be determined by the tuning of the trombone or slide circuit 22, and, part of the impulse will be transmitted to the control electrodes over the transmission line 34 and be made to cause a disturbance in the high frequency circuit 26 connecting the deflecting electrodes. The latter disturbance, by suitably altering the length of the transmission line by means of adjustable slides 36, 38, will cause the deflecting electrodes to deflect the electron stream in the opposite direction. In this manner, self sustained oscillations will ensue, the transmission lines acting somewhat in the fashion of the well known feed back arrangement used in connection with triodes.

By suitably spacing the various electrodes, harmonic oscillations may be diminished or entirely done away with. That is, harmonic oscillations may be present but, as they will be of a much lesser intensity than those fundamental frequency oscillations corresponding in frequency to the tunings of the circuits, by suitably spacing and choosing the dimensions of target electrodes 18, 20, the harmonic oscillations of the electron stream may be prevented from causing any appreciable excitation of the circuits.

Moreover, the harmonic oscillations may be suppressed by inserting parallel tuned circuits (not shown) in the transmission line 34, tuned to the harmonic frequencies.

Modulation of the oscillatory energy set up in tuned circuit 22 may be accomplished by introducing modulating currents from transmitter 50 and amplifier 52 by means of transformer 44 to the accelerating anode cylinder 12 as shown. Modulated energy may then be taken from the circuit by means of a transmission line 46 and transmitted by a suitable radiating antenna 48.

Having thus described my invention, what I claim is:

1. In a cathode-ray oscillating system, means for producing a stream of electrons, deflecting electrodes adjacent said stream, target electrodes in the path of said stream, a tuned circuit consisting of a pair of parallelly disposed conductors, each conductor having uniformly distributed inductance and capacity throughout its length coupled to said target electrodes, a tuned circuit consisting of a pair of parallelly disposed conductors having uniformly distributed inductance and capacity throughout their lengths coupled to said deflecting electrodes, and means comprising a pair of parallelly disposed conductors having uniformly distributed inductance and capacity throughout their lengths for coupling the circuits together whereby continuous oscillatory deflection of said electron stream ensues.

2. In a cathode-ray oscillatory system, the combination of means for producing a stream of electrons, deflecting electrodes adjacent said stream for deflection thereof, target electrodes in the path of the deflected stream, a tuned circuit comprising a U-shaped conductor system connected to the target electrodes, a tuned circuit comprising a U-shaped conductor system connected to the deflecting electrodes, and a two-conductor transmission line coupling the tuned circuits together whereby continuous oscillation of said electron stream from one target to another ensues, the conductors of said transmission line having uniformly distributed inductance and capacity throughout their lengths.

3. In a cathode ray oscillating system, means for producing a stream of electrons, two deflecting electrodes adjacent said stream, a U-shaped conductor coupling together said two deflecting elec-

trodes, two targets in the path of the deflected electron stream, a U-shaped conductor coupling together said two targets, means for supplying suitable potentials to said U-shaped conductors at voltage nodal points on said conductors, and connections from the legs of one U-shaped conductor to the legs of the other U-shaped conductor for causing continuous oscillatory deflection of said stream, said connections being adjustable over the legs of said U-shaped conductors.

4. In a cathode ray oscillating system, means for producing a stream of electrons, two deflecting electrodes adjacent said stream, a U-shaped conductor coupling together said two deflecting electrodes, two targets in the path of the deflected electron stream, a U-shaped conductor coupling together said two targets, a source of negative potential connected to said first U-shaped conductor at one of its voltage nodal points, a source of positive potential connected to said second U-shaped conductor at one of its voltage nodal points, and a pair of wires capacitively coupling the legs of said first U-shaped conductor to the legs of said second U-shaped conductor, whereby continuous oscillatory deflection of said stream ensues, said pair of wires being adjustable over the legs of said U-shaped conductors.

5. In a cathode ray oscillating system, means for producing a stream of electrons, two deflecting electrodes adjacent said stream, an accelerating electrode between said means and said deflecting electrodes, a U-shaped conductor coupling together said two deflecting electrodes, two targets in the path of the deflected electron stream, a U-shaped conductor coupling together said two targets, means for supplying suitable potentials to said U-shaped conductors at voltage nodal points on said conductors, and connections from the legs of one U-shaped conductor to the legs of the other U-shaped conductor for causing continuous oscillatory deflection of said stream, means in circuit with said accelerating electrode for modulating the oscillations produced, a utilization circuit, and a pair of wires extending from said utilization circuit to points on the legs of said second U-shaped conductor which are oppositely disposed with respect to the voltage nodal point on said conductor to which potential is supplied.
